INVENTOR:

Hugo Reisiger
By Mr Wallace White
ATTY.

UNITED STATES PATENT OFFICE.

HUGO REISIGER, OF ROTTERDAM, NETHERLANDS.

BENCH-SCREW.

1,345,403.

Specification of Letters Patent. Patented July 6, 1920.

Application filed August 14, 1919. Serial No. 317,574.

To all whom it may concern:

Be it known that I, HUGO REISIGER, a subject of the Kingdom of Netherlands, residing at Rotterdam, Netherlands, have invented certain Bench-Screws, of which the following is a specification.

This invention relates to a bench-screw or vise, and more particularly to improved means by which the movable jaw can be quickly brought into operative relation with the fixed jaw and locked against retractive movement and by means of which the movable jaw is automatically released when the work is disengaged, one of the objects of the invention being to provide a pair of clutches pivotally mounted on one of the jaws and a depending member carried by the other jaw and adapted to be engaged by said clutches in such a manner that the movable jaw is not only prevented from moving backward but is forced into closer contact with the fixed jaw or with the work between the jaws, the organization being such that the vise is capable of accommodating work of considerable length.

With the foregoing and other objects in view, which will appear as the description proceeds, the invention consists in the novel features of construction and combination of parts which will be more fully described hereinafter and particularly pointed out in the claims.

In the drawings accompanying and forming part of this specification—

Figure 1 is a perspective view illustrating a vise constructed in accordance with the present invention and having a piece of work gripped between its jaws;

Fig. 2 is a plan view showing the mechanism for holding the jaws in a work-engaging relation;

Fig. 3 is a sectional view of the fixed jaw and the operating parts carried thereby, taken approximately on the line A—B of Fig. 2; and

Fig. 4 is an end elevation of the vise.

Similar characters of reference designate the same parts in the different figures of the drawings.

The vise, in the preferred form herein illustrated, comprises a fixed jaw 1 provided with a lower bed or plate having means, such as perforated ears 1^a for securing it to a bench or other suitable support, and a movable jaw 2 provided with an extension or bed 2^a, which beds are slidable one

against the other. In the lower bed or extension of the jaw 1 are formed a pair of longitudinally extending recesses or grooves, in which are located for sliding movement 60 a pair of rods 3, each of which is provided at one end thereof with an open-ended recess that is adapted to straddle a cross member or trestle 4 that is slidable relatively to the extension or bed of the fixed jaw 1. 65 The opposite ends of the rod 3 are in contact with a member herein shown as a nut 5, having a threaded opening therethrough adapted to receive a screw 6, which rotates in bearings in the walls of the jaw 1, one 70 end of the screw passing to the exterior of the jaw 1 and provided with a head 7 having an opening therethrough adapted to receive a handle or lever for rotating the screw. The opposite end of the screw is 75 swiveled in the end wall 8 of the extension or bed of the jaw 1. It will thus be seen that by rotating the screw 6 the nut 5 may be moved forward or backward.

As herein shown, the cross member or 80 trestle 4 is of approximately U-shape formation, having right-angular portions at its ends, each provided with an opening through which passes a bolt 10. A pair of clutches 11 are mounted on the extension or 85 bed of the jaw 1 by means of a pivot 12, which passes up through an opening in the bed. The clutches 11 are provided each with an elongated slot 9 adapted to receive the bolt 10 which passes through the angular extension of the cross member 4 for permitting adjustment of the clutches as the cross member slides on the lower bed, the bolts 10 being retained in position by means of washers and nuts, as shown in Fig. 4. 90 The clutches 11 are provided at the ends opposite their pivotal connection with the cross member, each with a cam formed head 13, the end of which is somewhat rounded or curved, as shown clearly in Fig. 2. The extension or bed of the movable jaw 2 is provided at its under face with a longitudinally depending portion 14 which is adapted to slide between the heads 13 of the clutches 11. As clearly shown in Fig. 4, the under 105 surface of the bed of the movable jaw 2 is approximately T-shaped in cross-section, and the lower bed is provided with a pair of longitudinally extending upstanding portions 15 shaped to conform to the depending side portions of the T so as to form a 110 guide therefore and permit the said bed of

the jaw 2 to be slid on the bed of the jaw 1, while the stem of the T forms the depending portion 14 adapted to slide between the clutches. This depending portion 14, as indicated in Fig. 2, extends only the length of the bed of the jaw 2, and does not continue into the space below the overhanging portion of the jaw, so that the jaws when brought together to clamp a piece of work 10 between them have a clear space for permitting long pieces of work to be held between the jaws, as illustrated in Fig. 1.

It is thought that the operation of the device will be clear from the foregoing description. When out of operation, the heads 13 of the clutches 11 are normally sufficiently far apart to permit the depending portion 14 of the upper bed to slide freely between them. When it is desired to clamp a piece of work between the jaws, the work is placed in position and the jaw 2 slid on the bed of the jaw 1 until the work is engaged between the jaws. Thereupon the operator rotates the screw 6 by means of the handle 7' in the proper direction, as, for instance, to the left, to cause the nuts 5 to exert pressure on the end of the rod 3, which in turn cause the cross member 4 to slide and thereby swing the clutches 11 on their pivots 12 and cause 30 the cam heads 13 to firmly engage the depending member 14 of the slidable jaw. It will thus be seen that, because of the pivotal action of the clutches and their cam formation, that upon turning the screw 6 some- 35 what further the heads 13 of the clutches will force the jaw 2 into firm engagement with the work.

From the foregoing it will be seen that I have provided an improved construction of 40 a vise by means of which the jaws can be brought gradually into firm engagement with the work, so as to avoid injury thereto, and at the same time it is impossible for the work to slide away while being operated on. 45 This construction has the advantage that, while holding the piece of work with one hand, the operator can slide the movable jaw easily against it with the other hand and thereafter, by a slight rotation of the 50 screw 6, cause the clutches to firmly engage the depending member 14 and not only pre-

vent retrograde movement of the jaw 2, but force it into firmer engagement with the work. It will also be observed that, by reason of the flat formation of the upper surface of the bed of the jaw 2, it may be used as a table, which at times is very convenient. 55

While I have described in detail the structure herein illustrated, it is to be understood that I do not thereby limit my invention to 60 the precise features of construction shown, as I am aware that many mechanical changes and modifications may be made therein without departing from the spirit and scope of the invention as set forth in 65 the appended claims.

Having thus described my invention, what I claim is:

1. A vise, comprising a fixed jaw and a movable jaw, a pair of pivotally mounted 70 clutches carried by one of said jaws, a depending member carried by the other of said jaws in position to be gripped by said clutches when the jaws are brought into work-engaging relation, and means for operating said clutches, and including a cross member slidably with relation to the jaws and pivotally connected to said clutches, and a pair of rods slidable relatively to the jaws and in operative engagement with said cross 75 member.

2. A vise, comprising a pair of jaws, one fixed and the other slidable relatively thereto, a cross member slidably carried by said fixed jaw, a pair of rods slidably carried by 80 the fixed jaw in operative engagement with said cross member, a pair of clutches pivotally carried by said fixed jaw and pivotally connected to said cross member, a depending member carried by said slidable jaw and 85 adapted to slide between said clutches, and means carried by the fixed jaw for sliding said rods thereby to cause said clutches to grip said depending member and force the slidable jaw toward the fixed jaw. 90

95 In testimony whereof I affix my signature in presence of two witnesses.

HUGO REISIGER.
